WALTER H. SMITH, OF WILKINSBURG, PENNSYLVANIA, ASSIGNOR TO WESTINGHOUSE ELECTRIC & MANUFACTURING COMPANY, A CORPORATION OF PENNSYLVANIA.

CONTROL APPARATUS.

Application filed September 16, 1926. Serial No. 135,980.

This invention relates to relay control apparatus primarily designed for controlling actuating mechanisms for pantagraph trolleys and the like.

- The object of the invention, generally stated, is the provision of relay control apparatus that shall be simple and efficient in operation and capable of being readily and economically manufactured.
- 10 A more specific object of the invention is to provide for the actuation of a pantagraph or trolley pole automatically, upon the flow of an excessive current, or manually, when desired.

- 15 Another object of the invention is to facilitate the resetting of a pantagraph-actuating device after it has functioned to lower the pantagraph.

Other objects of the invention will, in part, be obvious and, in part, appear herein-after.

The invention, accordingly, is disclosed in the embodiment thereof shown in the accompanying drawing and comprises the structural features, the combination of elements and the arrangement of parts that will be exemplified in the construction hereinafter set forth, and the scope of the application of which will be indicated in the claims.

For a fuller understanding of the nature and objects of the invention, reference may be had to the following detailed description, taken in connection with the accompanying drawing, in which

Fig. 1 is a view, in side elevation, of a control relay and contacting device constructed in accordance with this invention; and

Fig. 2 is a diagrammatic view showing how the relay and contacting device may be connected for controlling the actuation of a pantagraph.

Referring to the drawing, the reference character 10 designates a relay panel on which the control relay, shown generally at 11, is mounted. As illustrated, the relay 11 comprises an overload coil 12 and an armature 13 which is pivotally mounted on the relay panel at 14.

The overload relay coil 12 is provided with a core 15, which is disposed in alignment with the head 16 of the armature 13. As will be readily understood, the number of turns in the coil and the size of the con-

ductor constituting the coil will depend upon the operating conditions.

As will be observed, a contact carrier 17 is associated with the armature 13. In this particular construction, the contact carrier 17 is pivotally mounted on the panel 10, below the armature, by means of a pin 18. However, it is to be understood that the contact carrier 17 may be set in a number of different positions relative to the armature 13 without in any way affecting the operation of the device.

In order that the air gap between the core 15 and the head 16 of the armature may be varied, the former is adjustably mounted in the coil 12. As shown, a shank 44, provided on the upper end of the core 15, is engaged by a nut 46 by means of which it may be set in different positions relative to the armature.

With a view to utilizing the armature 13 and contact carrier 17 for establishing certain circuits for the control of the pantagraph actuating mechanism that will be described hereinafter, contact members are mounted on them. As shown, two contact members 19 and 20 are mounted in spaced relation on the contact carrier 17, and a single contact member 21 is mounted on an extension 22 of the armature 13.

The upper end of the contact member 20 is made substantially L-shaped so that it may be engaged by the contact member 21 to lock the contact carrier 17 in a predetermined position. The other contact member 19 slopes gradually downward from the top of the contact carrier, so that, when the contact member 21 rests thereon, the contact carrier may be rotated counter-clockwise to set the contact member 21 in engagement with the contact member 20 without raising the armature member 22. A resilient member, such as a spring 23, is connected between the extension 22 of the armature 13 and the lower end of the contact carrier 17. In this manner, provision is made for continuously urging the contact member 21 toward the contact carrier 17. Further, when the armature 13 is raised to release the contact carrier 17, the spring 23, then actuated by the armature, exerts a pull on the carrier 17 and rotates it clockwise.

Referring now, in particular, to Fig. 2, a spring-raised, air-pressure lowered, pantagraph 24 is shown connected by a conductor

40 to the primary winding of a transformer 25. The secondary of the transformer is connected across a motor 26, which may be utilized for propelling a vehicle, for example. An auxiliary series transformer 42 is energized from conductor 40 for a purpose to be set forth.

In order to lower the pantograph to disconnect it from the trolley line 27, an air cylinder 28 is connected, through a pipe line 29 and an electromagnetically controlled valve 30, to a train air line, as indicated, such elements being usually provided on trains and street-cars for conveying compressed air to actuate the air brakes. The valve 30 is of the two-way type, and serves to establish communication between the air line and the cylinder 28, when electrically energized, and to connect the pipe line 29 to the exhaust 31, when deenergized.

As illustrated, a piston 35 is slidably mounted in the air cylinder 28 and is connected to a bell crank 36. The lower end of the bell crank 36 is connected to the pantograph 24 by a cable 37, extending around a pulley 38. Consequently, when air is admitted to the cylinder 28, the piston 35 is projected to the left, as viewed in the drawing, turning the bell crank 36 counter-clockwise and thereby drawing the pantograph downward.

When the air is exhausted from the cylinder 28, the springs, normally provided in the pantograph, serve to raise it into engagement with the trolley line 27. The structure of the pantograph is not described herein, since such devices are well known to those skilled in the art.

In order to effect the manual control of the pantograph-actuating mechanism, the valve 30 is connected to the contact member 21 by a conductor 32. The supply of electrical energy to the valve may be controlled by means of a manually operable switch 33 which is connected between the contact member 20 and any suitable source 34 of electrical energy.

Assume now that the contact carrier 17 is set with the contact member 20 in engagement with the contact member 21, as illustrated, and that it is desired to lower the pantograph in order to deenergize the motor circuit. The switch 33 is closed manually, and current flows from the source 34, through the conductor 39, contact members 20 and 21, conductor 32 and the coil of valve 30 to the source of supply. In this manner, the valve is energized and the cylinder 28 is connected to the train air line. The piston 35 is moved to the left and the pantograph lowered in the manner hereinbefore described.

If the contact members 20 and 21 are set in engagement when an excessive current flows through the pantograph 24 and the

conductor 40, leading to the primary winding of the transformer 25, for any reason, such as a short-circuit occurring in the primary winding of the transformer, as indicated by dotted lines at 41, then a heavy current 70 is induced in the auxiliary series transformer coil 42, which is connected to the overload relay coil 12. The flow of a predetermined current in the relay coil 12 effects the energization of the core 15 and 75 raises the armature 13. The contact carrier 17 is thus released, and the raising of the armature 13 causes the spring 23 to rotate the carrier 17 clockwise to set the contact member 19 in alignment with the contact member 21. When the contact members 21 and 19 engage, current flows from the source 34, through conductor 43, contact members 19 and 21, conductor 32, and the coil of the valve 30, to the source of supply. 80

Air is thus admitted to the cylinder 28, and the pantograph 24 is lowered. In order to release the pantograph, the carrier 17 may be rotated manually counter-clockwise to interrupt the valve circuit. 90

Since various changes may be made in the above-described construction and arrangement of parts, and different embodiments of the invention may be made without departing from the scope thereof, it is intended that all matter contained in the above description or shown in the accompanying drawing shall be interpreted as illustrative and not in a limiting sense. 95

I claim as my invention:

1. In control apparatus, in combination, a contact carrier disposed to be set in a plurality of positions, contact members mounted in spaced relation on the carrier, a movable armature associated with the carrier, a contact member provided on the armature and disposed to engage the carrier contact members, means for actuating the armature and means operated by the armature for setting the carrier. 100

2. In control apparatus, in combination, a contact carrier disposed to be set in a plurality of positions, contact members mounted in spaced relation on the carrier, a movable armature associated with the carrier, a contact member provided on the armature and disposed to engage the carrier contact members, means for actuating the armature, and means operated by the armature for setting the carrier, said carrier-setting means being disposed to tend continuously to establish engagement between the armature contact member and carrier contact members. 115

3. In control apparatus, in combination, a contact carrier disposed to be set in a plurality of positions, contact members mounted in spaced relation on the carrier, a movable armature associated with the carrier, a contact member provided on the carrier, 125

armature and disposed to engage the carrier contact members, means for actuating the armature, and means operated by the armature for setting the carrier, said armature 5 contact member being disposed to lock the carrier in a predetermined position.

4. In control apparatus, in combination, a contact carrier disposed to be set in a plurality of positions, contact members 10 mounted in spaced relation on the carrier, a movable armature disposed in alignment with the carrier, a contact member mounted on the armature, means for actuating the armature, and means disposed for actuation 15 by the armature to set the carrier in a predetermined position, said carrier-setting means being adapted to continuously urge the armature toward the carrier to establish engagement between the armature contact 20 member and the carrier contact members.

5. In control apparatus, in combination, a pivotally mounted contact carrier, a plurality of contact members mounted on the contact carrier, an armature associated 25 with the carrier, a contact member mounted on the armature and disposed to engage the carrier contact member and to be utilized

for locking the carrier in a predetermined position, means for actuating the armature to release the contact carrier, and means 30 actuated by the armature for setting the contact carrier, when released, in a predetermined position.

6. In control system for actuating pantographs, in combination, means for actuating a pantograph, and means for controlling the pantograph-actuating means comprising a contact carrier provided with a plurality of contact members, an armature associated with the contact carrier, a contact member 40 provided on the armature and disposed to engage the armature contact members, said armature contact member being disposed to engage a carrier contact member to lock the contact carrier in a predetermined position, an overload relay coil disposed to actuate the armature to release the contact carrier upon the flow of a predetermined current through the pantograph, and means actuated by the armature to move the contact carrier. 45

In testimony whereof, I have hereunto subscribed my name this 8th day of September, 1926.

WALTER H. SMITH.
